UNITED STATES PATENT OFFICE.

ELONZO A. PENNINGTON, OF DALARK, ARKANSAS.

CROSSING SIGNAL.

Application filed May 9, 1922. Serial No. 559,562.

To all whom it may concern:

Be it known that I, ELONZO A. PENNINGTON, a citizen of the United States, residing at Dalark, in the county of Dallas and 5 State of Arkansas, have invented new and useful Improvements in Crossing Signals, of which the following is a specification.

My present invention has reference to a safety device for railway crossings.

10 In carrying out my invention it is my purpose to arrange at a railway crossing a visible and audible alarm which shall be automatically operated by a train approaching the crossing from either direction.

15 A further object is to produce an automatic danger signal for railway crossings characterized by simplicity in construction and reliability and efficiency in practical use.

20 To the attainment of the foregoing, the invention consists in the improvement as hereinafter described and definitely claimed.

In the accompanying drawings forming part of this specification.

25 Figure 1 is a side elevation illustrating the application of my improvement.

Figure 2 is a top plan view thereof.

Figure 3 is an enlarged view of the track apparatus, parts being broken away and 30 parts being in section.

Figure 4 is an enlarged sectional view of the boxing 27.

Figure 5 is an enlarged detail sectional view on the line 5—5 of Figure 3.

35 At the corners of a railway crossing I arrange my improved signal. The improvement may be positioned at one corner or two of the diagonally opposed corners, or at all of the corners as desired, but in the drawings

40 I have shown the same arranged at only one corner. The rails of the track are indicated by the numeral 1, and at a suitable distance from one or both sides of the crossing I arrange alongside one or both of the

45 rails a deppressible member 2 which is designed to be contacted by the flanges of the wheels passing over the track. The deppressible member 2 is in the nature of a plate that has its upper edge arched or rounded

50 upwardly from its ends to its center, the said central portion being normally projected above. The plate, or more strictly speaking the bar 2 projects through an opening in a housing 3 which is spiked or otherwise secured on the supporting ties of the rails.

55 The bar 2 is centrally formed with a depend-

ing portion in the nature of a lug 4 to which are pivotally connected oppositely directed arms 5 respectively. Each arm is pivotally secured by means 6 that pass transversely 60 through the housing 3, and the outer ends of the arms 5 have adjustably secured thereon weights 7. By this means it will be noted that the rounded central portion of the bar 2 will be projected above the tread surface 65 of the rail.

The pivots 6, to the opposite sides of one or both of the arms have arranged therearound spacing rolls 8, and secured to what may be termed the outer corner of the housing there 70 is one end of a cable 9. This cable is trained around suitable grooved rollers 10 respectively, let in openings or depressions in the lower corners of the bar 2, and is trained over a grooved sheave 11 journaled in bearings 75 at the front corner of the housing. The cable 9 is further trained over additional oppositely disposed upper and lower sheaves 12 and 13 respectively and has its end connected to a contractile spring 14 which in turn is 80 connected to a rod (or cable) 15 that is received through a suitable opening in a box-like housing 16 and is connected to one end of a rocker lever 18 pivoted off its center, as at 19 in the said housing 16. Between the 85 lever 18 and the housing, opposite its connection with the rod 15 there is a contractile spring 20. The opposite or free end of the lever has secured thereto a cable 21 trained around a sheave wheel 22 journaled in the 90 housing 16 and directed through an opening in the top of the housing. The cable 21 may be and preferably is connected with a rod which is directed at a downward angle toward the crossing.

95 The signal includes a hollow standard 23. In the standard, adjacent to the bottom thereof there are grooved wheels or sheaves 24 around which is trained the flexible end of the element 21.

100 The hollow standard has at its upper end a yoke-like extension that includes spaced parallel arms 25 respectively. In the standard 23, below the arms 25 there are journaled spaced grooved wheels 26 respectively. On the sides of the standard opposite the grooved wheels 26 there are outwardly directed boxings 27, in each of which there is journaled a grooved wheel 28 respectively. Secured to the flexible element 21 that is 110 trained around the sheave 24 there is a rod 29 which is directed centrally through the

standard 23. The rod 29 passes through a bearing lug 29' in the standard. Surrounding the rod 29 and in contact with the lug 29' there is a spring 30. The spring has 5 one end secured to the rod to influence the same in a downward direction for a purpose which will presently be understood. The upper end of the rod 29 has secured thereto a coiled spring 31, and to the outer end of 10 the spring there are connected links 32 respectively. These links are received in eyes in the ends of semaphore arms 33 respectively. Each arm passes through a bearing in the boxing 27 in the respective arms 25. 15 Between the bearings for the semaphore arms and the boxings 27 there are raceways for anti-frictional balls 34 whereby the arms may be freely moved on their pivots and friction between the moving parts reduced as 20 much as possible.

Secured to the rod 29 below the grooved wheels 26, and passing through openings and guided over the respective opposed pairs of grooved wheels are the divided ends 35 25 of a flexible element. On the upper ends of the arms there is journaled in suitable bearings 36 a shaft 37. This shaft has its ends cranked, and secured to the said cranks are the said strands 35. On the shaft there is 30 secured a bell 38, and loosely supported in the bell there is a striker 39 therefor.

On the rod 29 there may be secured a clevis-like member 40 to which may be connected flexible elements that are trained 35 around certain of the sheaves 24 and that are directed in a manner as heretofore described to a depressible element similar to the bar 2 arranged adjacent to the siding or switch rails of the system.

40 It is thought that the foregoing description, when taken in connection with the drawings will fully set forth the construction, operation and advantages of the improvement. It is to be understood that the bar 2 45 and the housing therefor are located a considerable distance away from the crossing and that a train approaching the crossing will, upon the depression of the said bars swing the semaphore arms to signalling posi-

tion. The swinging of the bars will turn the 50 crank shaft which will sound the bell and thus give audible alarm to persons approaching the crossing that a train is nearing the crossing. The parts automatically return to initial position when pressure on the bar 2 55 is released. All of the parts are cushioned by the spring elements attached thereto. The weights, which influence the bar 2 are, as previously stated, adjustable and therefore any slack in the cable 9 may be compensated 60 for after shortening the said cable. It is, of course, to be understood that the showing and description refer only to a satisfactory embodiment of the improvement as it now appears to me and that I may make such 65 changes therefrom as fall within the scope of what I claim.

Having described the invention, I claim:—

In a crossing signal for railways, a hollow standard having spaced arms extending 70 from the top thereof, a boxing on each arm, a semaphore blade passing through and pivotally supported in each of the boxings, a shaft journaled in bearings on the ends of the arms, and the ends of the shaft being 75 cranked, a bell carrying a striker supported on the shaft, a rod disposed centrally in the standard, guide means therefor, spring buffer means between the guide means and the rod, a spring secured to the upper end 80 of the rod, flexible elements secured to the spring and to the respective semaphore blades, branch flexible elements secured to the rod, grooved wheels journaled in the standard around which said flexible elements 85 are trained, and said flexible elements being connected to the cranked ends of the shaft, a yieldably supported tread bar along one side of one of the rails of the track and designed to be forced downwardly by the 90 wheels of a rolling stock passing over the track, flexible elements secured to the ends of the rod, guide means therefor, and one of said flexible elements being connected to the tread bar and the other to the rod in the 95 standard.

In testimony whereof I affix my signature.
ELONZO A. PENNINGTON.
